CLAIM

The ornamental design for a cover for a finger ring, as shown and described.

DESCRIPTION

FIG. 1 is a front elevation view of a cover for a finger ring showing my new design in a disassembled configuration of use;

FIG. 2 is a front elevation view of the cover for a finger ring, shown in an assembled configuration of use;

FIG. 3 is a rear elevation view thereof;

FIG. 4 is perspective view of the two components of the cover for a ring, in a disassembled configuration for clarity of illustration; and,

FIG. 5 is another perspective view of the two components of the cover for a ring, in a disassembled configuration for clarity of illustration.

The broken line portions shown in FIGS. 2 and 5 illustrate environmental subject matter only and form no part of the claimed design.
